UNITED STATES PATENT OFFICE.

DAVID L. MCKENZIE, OF WINNIPEG, MANITOBA, CANADA.

LUBRICATING COMPOUND.

SPECIFICATION forming part of Letters Patent No. 351,195, dated October 19, 1886.

Application filed June 10, 1886. Serial No. 204,720. (No specimens.)

To all whom it may concern:

Be it known that I, DAVID L. MCKENZIE, of Winnipeg, Manitoba, Canada, have invented a new and useful Improvement in Lubricating Compounds, of which the following is a specification.

My invention is in the nature of an improved lubricating compound for car-axle boxes, journal-boxes, and all sliding bearings, designed to reduce friction to a minimum, and to preserve for a long time its lubricating qualities without decomposition or deterioration.

In preparing my compound I take the following ingredients and proportions: Animal fat, five per cent., by weight; mineral-oil refuse, seventy-five per cent., by weight; slaked lime, fifteen per cent., by weight; manganese, (black oxide,) five per cent., by weight. These I mix thoroughly together by heating to boil-

ing, and the compound is then ready to be put up for use, which compound is, when cool, about the consistency of paste or of a semi-fluid character.

It is not necessary that the exact proportions named should be adhered to, as a little more or less of any of the ingredients will not involve any substantial departure from my invention.

Having thus described my invention, what I claim as new is—

The lubricating compound herein described, consisting of animal fat, mineral-oil refuse, slaked lime, and manganese, in or about the proportions named.

DAVID L. MCKENZIE.
